VENTILATOR FOR MOTOR VEHICLE WINDOWS

Abraham Sprung and Leo W. Weiss,
Brooklyn, N. Y.

Application April 28, 1948, Serial No. 146,004

Term of patent 14 years

(Cl. D14—6)

To all whom it may concern:

Be it known that we, Abraham Sprung, and Leo W. Weiss, citizens of the United States, residing in Brooklyn, in the county of Kings and State of New York, have invented a new, original, and ornamental Design for Ventilator for Motor Vehicle Windows, of which the following is a specification, reference being had to the accompanying drawing, forming a part thereof.

In the drawing:

Figure 1 is a perspective view of a ventilator for motor vehicle windows, showing the new design.

Figure 2 is a front elevational view thereof.

Figure 3 is a top plan view thereof.

Figure 4 is a right hand end view thereof; and

Figure 5 is a sectional view thereof, the section being taken on line 5—5 of Figure 2.

The drawing illustrates the ventilator as having a symmetrically designed ventilator portion and an unevenly designed flange portion.

We claim:

The ornamental design for a ventilator for motor vehicle windows, as shown.
